G. L. Colbie

UNITED STATES PATENT OFFICE.

GUS L. COLBIE, OF BROOKLYN, NEW YORK.

MOUNTING FITTING.

Application filed June 23, 1920. Serial No. 391,208.

To all whom it may concern:

Be it known that I, Gus L. Colbie, a citizen of the United States, and a resident of the city of New York, borough of Brooklyn, in the county of Kings and State of New York, have invented certain new and useful Improvements in Mounting Fittings, of which the following is a specification.

The present invention relates to such mounting fittings as are commonly used for holding or mounting instruments such as speedometers, oil gauges, switches, etc., rigidly on the cowl or dash board of automobiles, trucks, etc. While I am showing the present invention applied to a speedometer or similar instrument it is obvious that the said present invention can be applied to serve many different useful purposes and therefor is not confined to the few instruments above named, and it is intended that this patent shall cover the present invention as shown on the accompanying illustrative embodiments and herein described regardless of where same is applied.

It will however be understood that I do not limit myself to the exact structural details shown on the accompanying drawings and herein described, but my invention may be modified in detail and certain structural details varied from that shown without departing from the spirit of the invention.

The objects of the present invention are to provide an inexpensive, simple, durable, positive, easily applied and efficient mounting fitting for instruments, etc., as above and hereinafter stated.

Referring to the drawings Fig. 1 is an end elevation of a construction embodying the present invention in one form. Fig. 2 is a side view of Fig. 1. Fig. 3 is a side view of a somewhat different construction, and Fig. 4 is a front view of same. Fig. 5 is a side view of a third proposed structure, Fig. 6 being a plan view of Fig. 5.

As shown in Fig. 1 the present invention comprises lugs or projections "a" extending from the casing 1 of the instrument which we wish to mount. A circular member 2 encircles the casing 1, said member 2 is made open with ends formed to receive a screw 3 and nut 4. On the member 2 are formed suitable angles "b" to engage the lug "a", said lug "a" having an angle to correspond with the angle on the member

2. On the construction shown in Fig. 1 the angles on both sides would be made so that a downward pressure on the member 2 would cause same to move in the direction of the arrow "c" thereby clamping the instrument on the instrument board 5 by reason of the pressure between the flange "d" and the member 2. The flange *d* may be replaced by a shallow bead, shoulder, 65 plurality of lugs or any suitable means of abutment. Between the topmost surface of the casing 1 and the encircling member 2 a suitable amount of space *e* is provided to permit downward movement of the member when the screw 3 is manipulated. In Figs. 3 and 4 the member 2 is composed of two parts, this construction may in certain cases be preferable to the aforementioned type, such as when it is impossible to 75 encircle the instrument or for other reasons. Figs. 5 and 6 show a third method of constructing the member 2, in this construction there may be only one clamping element or one side of the member 2, or 80 two of the clamping elements depicted in Figs. 5 and 6 arranged oppositely and actuated by the same tightening means or by separate means.

Having thus described my invention what 85 I claim as new and desire to secure by Letters-Patent are:

1. A device of the class described comprising in combination, an apertured support, an instrument adapted to enter the 90 aperture of said support and having a flange to positively engage said supporting structure at one side thereof, a member partly encircling said instrument casing at the other side of said supporting structure and having wedge portions thereon to engage suitable abutments on the instrument and a screw adapted to positively clamp said instrument to said supporting structure by effecting a wedging action of 95 the above-mentioned wedge portions between said abutments and the supporting structure.

2. A device of the class described comprising in combination, an apertured support, an instrument adapted to enter the aperture of said support and having means to positively engage said supporting structure at one side thereof, a member associated with the said instrument at the other side of said supporting structure and having a wedge portion thereon to engage a suit-

able abutment on said instrument and a screw adapted to positively clamp said instrument to said supporting structure by effecting a wedging action of the above-mentioned wedge portion between said abutment and the supporting structure.

3. A device of the class described comprising in combination, an apertured support, an instrument adapted to enter the aperture of said support and having means to positively engage said supporting structure at one side thereof, two co-acting members associated with the said instrument at the other side of said supporting structure and having wedge portions

thereon to engage suitable abutments on said instrument and positive means adapted to rigidly clamp said instrument to said supporting structure by effecting a wedging action of the above-mentioned wedge portions between said abutments and the supporting structure. ²⁰

In testimony whereof, I have hereunto set my hand at New York, N. Y., this 9th day of June, 1920.

G. L. COLBIE.
